CLAIM

The ornamental design for a test strip, as shown and described.

DESCRIPTION

FIG. 1 is a bottom view of a test strip;

FIG. 2 is a bottom perspective view of the test strip of FIG. 1;

FIG. 3 is a top view of the test strip of FIG. 1;

FIG. 4 is a top perspective view of the test strip of FIG. 1;

FIG. 5 is a front view of the test strip of FIG. 1;

FIG. 6 is a rear view of the test strip of FIG. 1;

FIG. 7 is a left side view of the test strip of FIG. 1; and,

FIG. 8 is a right side view of the test strip of FIG. 1.

The broken lines in the drawings are included for the purpose of illustrating portions of the test strip that form no part of the claimed design.
